AUTOMATIC WHEEL WASHER

Russel A. Van Brakel, Wooddale, Ill., assignor to Haverberg Auto Laundry Equipment Co., Inc., a corporation of Illinois

Filed July 8, 1963, Ser. No. 293,474
14 Claims. (Cl. 15—21)

The present invention relates to automatic wheel washers for car washes of the type wherein a cleaning agent is nozzle directed onto the vehicle wheel to be washed and a non-spinning brush is urged thereagainst while the wheel is spun by live rollers and while the vehicle is being pulled along through the car wash. More particularly the invention relates to such a wheel washer wherein several wheel spinning rollers are used with their axes remaining stationary during the wheel washing operation as distinguished from those wheel washers in which a pair of wheel spinning rollers are mounted on a carriage which moves along with the vehicle during the wheel washing operation.

In important object of the invention is to provide an improved wheel washer of the stationary wheel spinning roller type in which the scrubbing brush and nozzles for the steam-detergent or other cleaning agent are automatically accurately positioned and controlled relative to the vehicle for maximum effectiveness during the entire wheel washing cycle.

Another important object is to provide an improved such machine which is unusually reliable and trouble-free and yet can handle a high volume of vehicles while maintaining its cleaning effectiveness.

Other more particular objects and advantages of the invention will, with the foregoing, appear and be understood in the course of the following description and claims, the invention consisting in the novel construction and in the adaptation and combination of parts hereinafter described and claimed.

In the accompanying drawings:

FIGURE 1 is a fragmentary plan view of a wheel washing operation incorporating one embodiment of the present invention.

FIG. 2 is a somewhat schematic fragmentary vertical sectional view on line 2—2 of FIG. 1.

FIG. 3 is an enlarged-scale illustration of said embodiment shown partly in plan and partly in horizontal section.

FIG. 4 is a side elevational view taken from the vantage point shown by 4—4 in FIG. 3 with the scale enlarged.

FIG. 5 is a fragmentary transverse vertical sectional view on line 5—5 of FIG. 3, using the same scale as that of FIG. 4.

FIG. 6 is a fragmentary transverse vertical sectional view on line 6—6 of FIG. 4.

FIG. 7 is a longitudinal vertical sectional view on line 7—7 of FIG. 3 with the scale the same as that of FIGS. 4, 5 and 6.

FIG. 8 is a schematic view of the air control system.

FIG. 9 is a fragmentary top plan view illustrating a second embodiment; and

FIG. 10 is a longitudinal vertical sectional view on line 10—10 of FIG. 9.

As above indicated by way of introduction, the wheel washer of the present invention relies upon spinning of the wheels while in contact with a brush 25 to obtain a scrubbing action. As is well known in the art, this spinning is accomplished by a set of rollers 26 traversing the travel path of the vehicle while it is pulled over the rollers by an endless conveyor 27 continuing the length of the wash rack containing the wheel washer. For purposes of example, seven rollers have been shown with the

2

outer two being idlers and the other five being power driven as from a motor 28 by a chain drive 29. Activating and deactivating treadles 31—32 are mounted in the travel path of the conveyed vehicles before the first and after the last of the rollers 26, respectively.

In general, the illustrated embodiment of the invention comprises a stationary frame 33 anchored to the floor, a carriage 34 pneumatically powered by an air cylinder 35 to move the brush 25 against the wheel to be washed, and a holder assembly 36, for the brush and a pair of steam nozzles 30, which is slidably mounted on the carriage and powered to move the brush 25 along with the wheel as the related vehicle is pulled over the spinning rollers 26. A pair of such units can be mounted directly opposite one another with a single set of the wheel spinning rollers therebetween of a length to traverse the full width of the vehicles, or the units can each have their own set of rollers for the wheels on the respective side of the vehicles and be either directly opposite one another or staggered lengthwise of the wash rack at the opposite sides thereof. The latter condition has been shown in the drawings as an example.

Continuing to a detailed description of the illustrated embodiment, the stationary frame 33 has a center tubular housing 37 for the pneumatic cylinder 35 which is anchored to the outer end of the housing and has its piston rod 35a pin-connected at 35b to the center of the carriage 34. The frame of the carriage 34 comprises a channel 40 extending parallel to the conveyor 27 and a pair of parallel spaced tubes 41—42 welded at their inner ends to the web of the channel and extending outwardly at right angles thereto. These tubes 41—42 are slidably mounted in guide tubes 38—39 provided by the stationary frame at opposite sides of the center tube 37 and house a pair of air cylinders 43—44 which are each only charged with pressured air on the inner end (piston rod end) thereof, the outer end being vented. Pins 45 anchor these cylinders to the outer ends of their housing tubes and at their free ends the piston rods 43a—44a thereof have clevises 46 for pulleys 47—48. Respective cables 49—50 work on these pulleys and thread out of the inner end portions of the tubes 41—42 through respective inner and outer openings 51—52. The inner openings 51 are each bridged by a post 53 around which the respective cable 49—50 bends. Adjacent these posts 53 the cables have stud end fittings 54 anchored to angle brackets 55 in turn welded to the channel 40. The outer openings 52 are each bordered top and bottom by a pair of eyes 56 between which are journaled pulleys 57—58 for the cables 49—40, respectively. These cables are anchored at their outer ends on drums 59—60 made integral with sprockets 61—62 and are journaled on studs 63 which pass through brackets 64 welded to end plates 65 on the opposite ends of the channel 40. The studs are necked at their threaded free end portions and bear by the resulting shoulder against take-up plates 66 by action of their nuts 63a. To anchor the ends of the cables the drums 59—60 each have a chordal bore receiving the respective cable and intersected by a radial tapped hole for a set screw.

The pair of end plates 65 on the channel 40 project toward the conveyor 27 relative to the web of the channel and each projection, denoted 65a, has a pair of vertically spaced tubular sockets 67—68 extending therethrough and welded thereto in parallel relation to the channel. Upper and lower tubular rails 69—70 have their ends seated in these sockets and are fixed by vertical pins 71 extending down through the sockets. Riding on these rails 69—70 by a pair of sleeves 72—73 is the brush holder 36. The upper of these sleeves has a chain clip 75 welded on its outer face for receiving the ends of a chain 76 which passes around the sprockets 61—62. For a frame the holder 36 has a back plate 77 to which the sleeves 72—73

are welded and has front and rear end members 78-79 each having front and bottom brush retaining flanges. These flanges are complemental by a removable brush clamp 81 which is bolted to a top flange 80 overlying the sleeves. The stem nozzles 30 are also mounted on this clamp 81.

Trailing the brush holder 36 is a control valve assembly having a mounting plate 82 and a reach 83 welded at right angles to the rear end member 79 and joined at their free ends by a bridge 84. This bridge is tapped for an adjustable stop bolt 85 opposing a swing arm 86 which has an eccentric cam 87 at its root end. The pivot pin 88 for this cam is journaled in the members 82-83 and is retained by a screw 90 threaded into the latter. Downward swing of the arm 86 away from the stop 85 is resisted by a tension spring 91 which is anchored by a bracket 92 on the plate 82 and hooks through an opening in the arm. At its free end swing arm has journal-mounted thereon a follower roller 93 which projects toward the center of the wash rack so as to occupy a position behind the lower half of the wheel being washed. Consequently, whenever the roller 93 is forced against the back of the wheel the arm 86 swings downwardly and faces the cam 87 to close a self-opening valve 94 in the control system. This valve is bolted on the plate 82 directly above the pivot pin 88 so as to be open when the swing arm is generally horizontal and to be closed when the swing arm is forced downwardly in opposition to the spring 91. Flexible neoprene hoses interconnect the valve 94 with the other parts of the control system and are used in most other parts of the system to permit relative motion.

Directing attention to the schematic of the control system for the air cylinders 35, 43 and 44, high pressure air from a supply source enters the system through a manual valve 100, and after passing through an air filter 101 and filter lube unit 102 it forks with one branch leading to the cylinder 44 via a diaphragm valve 104, the swing-arm controlled valve 94, a shuttle valve 105, and dump valve 106, while the other branch supplies a pressure regulator 103 (about 100 p.s.i.). Between the latter and a pressure regulator 107 for step-down to supply low pressure air (about 8 p.s.i.) to the shuttle valve 105 and a complementing shuttle valve 108, the high pressure air is fed as the supply for a 3-way valve 110. This valve is controlled by the activating and deactivating treadles 31-32 as for example as shown in Patent No. 2,837,759, so that the supplied air is shuttled to pipe 111 when the activating treadle 31 is depressed and is shuttled to pipe 112 when the deactivating treadle 32 is depressed.

Pipe 111 branches to a pressure switch 113 for starting the motor 28 which drives the wheel-turning rollers 26 and continues to the activating end of the carriage moving cylinder 35 via a steam control valve 114, a stepdown pressure regulator 115 (to about 30 p.s.i.), and a dump valve 116. From the cylinder 35 the pipe 111 also branches at 117 to open the diaphragm valve 104. Thus, the steam valve 114 for supplying steam or steam-detergent to the nozzles 30 via flexible hoses, and the valve 104 in the circuit for activating the brush advancing cylinder 44, are automatically opened when, and only when, the carriage is in operating position with the brush 25 against a wheel. At the same time the brush advancing cylinder 44 is activated as dictated by the swing-arm controlled valve 94.

When the deactivating treadle 32 is depressed the valve 110 shuttles to supply pipes 118 and 119 rather than pipe 111. This causes the activating end of the carriage cylinder 35 and the pipe 117 to dump at valve 116, and the supply to the switch 113 and steam valve 114 to dump at the valve 110, while the deactivating end of the carriage cylinder and the high pressure side of shuttle valve 108 are being supplied by the pipes 118 and 119, respectively. The dumping of pipe 117 leading to the diaphragm valve 104 causes the latter to close and thereby

shuts off the supply of high pressure air to the brush advancing cylinder 44 which thereupon dumps through valve 106. The high pressure air supplied from the 3-way valve 110 to the shuttle valve 108 feeds therefrom into the brush returning cylinder 43 via a dump valve 120. Thus, depression of the deactivating treadle 32 causes the motor 28 for the wheel rollers 26 to be de-energized, the steam for the nozzles 30 to be shut off, and the brush and carriage to be returned.

Then, when the activating treadle 31 is depressed by the next wheel, the valve 110 again shuttles causing dumping of the return end of the carriage cylinder at the valve 110 via the pipe 118, dumping of line 119 at the valve 110, shuttling of valve 108, and dumping of brush return cylinder 43 through valve 120. At the same time the motor 28 is started to spin the rollers 26, the carriage 34 moves back out to force the brush 25 against the wheel, the brush advancing cylinder 44 is charged, and the nozzles 30 are supplied.

20 The simultaneous charging of the piston rod end of the cylinder 44 with high pressure air and dumping of the piston rod end of the cylinder 43 from high pressure to low pressure air causes the piston rod 44a to retract while permitting the piston rod 43a to be pulled outwardly against the mild resistance of the low pressure air. As a result the pulley 48 is retracted and unwinds the cable 50 from the drum 60 thereby turning the sprocket 62 in the direction advancing the top run of the chain 76. This pulls the clip 75 toward the sprocket 62 and hence 25 advances the brush assembly along the carriage rails 69-70. At the same time the chain 76 drives the sprocket 61 which in turn rotates the drum 59 and winds the cable 49 while tension is maintained thereon by the pulley 47 due to the low-pressure air supply to the piston rod 30 end of the cylinder 43.

When the carriage has advanced sufficiently relative to the wheel being washed the control valve 94 is closed by the resulting engagement of the follower roller 93 with the lower part of the wheel as earlier described. This 30 shuts off the supply of high pressure air to the brush advancing cylinder 44 and results in dumping thereof at valve 106. The wheel then moves ahead slightly relative to the follower roller 93 leaving the spring 91 free to raise the swing arm 86 and permit the control valve 94 to reopen and again charge the cylinder 44 to advance the brush assembly until the roller 93 is pressed hard enough against the back of the wheel to cause the cycle to be repeated. In actual practice such dumping and charging of the brush advancing cylinder is usually only 35 partial because of the throttling effect created by action of the cam 87 on the valve 94. The result of this action is to maintain the brush 25 and the surmounting nozzles 30 in substantially fixed washing position relative to the wheel while scrubbing pressure is maintained on the brush by the carriage cylinder 35. This washing position is 40 on the front part of the wheel whereat downward rotation of the wheel carries the cleaning agent (usually steam-detergent) jetting from the nozzles 30 directly into the brush.

When the wheel reaches and depresses the deactivating treadle 32, the resulting charging of the brush returning cylinder 43 with high pressure air and simultaneous dumping of the cylinder 44 from high pressure to low pressure air in the manner above described, immediately 45 causes the piston rod 43a with its pulley 46 to be retracted and permits the piston rod 44a with pulley 48 to be withdrawn. Consequently, the cable 49 unwinds from the drum 59 causing the sprocket to turn, pulling the upper run of the chain 76 toward the rear of the carriage thereby 50 returning the brush assembly. This movement of the chain also drives the sprocket 62 and responsively rewinds the cable 50 on the drum 60 while tension is maintained on the cable by the low pressure air in the cylinder 44. In this manner the return of the brush assembly is positive and rapid.

The embodiment of FIGS. 9 and 10 is somewhat simpler in that it substitutes a single double-acting air cylinder 200 for the two air cylinders 43 and 44, and eliminates the spooling drums 59 and 60. As a functioning counterpart of the carriage 34, there is provided a carriage 34' which is attached to the piston of the air cylinder 35 so as to be shifted inwardly toward and outwardly from the travel path of the car wheel to be washed. Guides are perforce provided as complements of the piston for said cylinder 35. The air cylinder 35, said guides, the trailing control valve assembly and its mounting structure are deleted from FIGS. 9 and 10 in order to simplify the illustration.

The double-acting air cylinder 200 has one of its ends footing against one end wall 201 of the carriage 34', this being the end wall which lies distal to said valve assembly, and extends therefrom longitudinally of the carriage for approximately half the length of the latter, receiving support for such inner end from the carriage back wall 203. The rod 204 of the associated piston extends from such inner end and carries a clevis 205. A pair of axially spaced sprocket wheels 206 and 207 are journaled by a pin 208 for free rotation in the space between the arms of said clevis, and taking a half-turn about these sprocket wheels are respective chains, as 209 and 210. Chain 209 has a bottom run dead-ended to the wall 201. A median run returns from the concerned sprocket wheel and takes a half-turn about a free-running sprocket wheel 211 which occupies a position adjacent such wall 201, thence extending by a top run to a clip 75' which, like the clip 75 of the first-described embodiment, is fixed to a counterpart 72' of the sleeve 72. The other chain 210 takes its half turn in the other direction about the related sprocket wheel 207, has a bottom run dead-ended to the carriage's other end wall 214, with a median run returning from the sprocket wheel 207 to pass about a free-running sprocket wheel 215 occupying a position adjacent wall 214, and thence to be anchored to a clip 75' at the side of the latter opposite the anchored end of the chain 209. The sprocket wheels 206 and 207 have twice the teeth of the sprocket wheels 211 and 215. Correlated to the schematic diagram of FIG. 8 it will be understood that the air hoses which connect with the two ends of the cylinder 200 correspond to the two lines which connect one with the air cylinder 43 and the other with the air cylinder 44.

It is believed that the invention will have been clearly understood from the foregoing detailed description of my now preferred illustrated embodiments. Changes in the details of construction may be resorted to without departing from the spirit of the invention and it is according my intention that no limitations be implied and that the hereto annexed claims be given the broadest interpretation to which the employed language fairly admits.

I claim:

1. A wheel washer comprising, means for advancing a wheel to be washed along a given travel path, means for rotating said wheel considerably faster, rim speed considered, than the bodily speed of the wheel while being moved along said travel path, an elongated carriage paralleling said travel path and presenting a track therealong, a brush and nozzle assembly slidably mounted on said track, anchored first double-acting means for moving said carriage at cross-angles to said travel path, second double-acting means carried by said carriage for moving said assembly along said track, and control means responsive to the travel of a wheel along said travel path for selectively activating said first and second double-acting means such as to cause said first double-acting means to move said carriage toward said travel path to bring said assembly into wheel engaging position and to cause said second double-acting means to advance said assembly along said track with the advancing wheel when said wheel is near the beginning of said track, and such as to cause said first double-acting means to

move said carriage away from said travel path to remove said assembly from wheel engaging position and to cause said second double-acting means to return said assembly to the beginning of said track when said wheel is near the end of said track.

2. The wheel washer of claim 1 in which said control means includes a control arm carried by said brush and nozzle assembly and arranged to extend into said travel path behind the wheel being washed when said assembly is in wheel engaging position, said control means deactivating said second double-acting means responsive to engagement of said arm with the back of said wheel whereby the advance of said assembly along said track is maintained at the same rate as the advance of said wheel along said travel path.

3. The wheel washer of claim 1 in which said control means includes a valve which, when closed, deactivates said second double-acting means and includes a control arm mounted on said brush and nozzle assembly to extend into said travel path behind the wheel being washed when said assembly is in wheel engaging position, said control arm being arranged and adapted to close said valve responsive to engagement of the arm with the back of said wheel whereby the advance of said assembly along said track is maintained at the same rate as the advance of said wheel along said travel path.

4. The wheel washer of claim 1 in which said second double-acting means comprises a reversible endless conveyor mounted on said carriage to extend along said track and connected to said brush and nozzle assembly for shuttling said assembly on the track, a pair of drums journal mounted on said carriage and operatively associated with said conveyor to turn in unison responsive to movement of said conveyor in either direction of travel, a pair of cables each having one of its ends anchored on a respective said drum, and double-acting fluid cylinder means carried by said carriage and operatively associated with said cables and with said control means for selectively pulling either of said cables and correspondingly releasing the other cable whereby the cable being pulled unwinds from its drum and responsively moves said conveyor and assembly while the cable being released winds on its drum responsive to turning of such drum by the conveyor.

5. The wheel washer of claim 1 in which said second double-acting means comprises a reversible endless conveyor mounted on said carriage to extend along said track and connected to said brush and nozzle assembly for shuttling said assembly on the track, a pair of drums journal mounted on said carriage and operatively associated with said conveyor to turn in unison responsive to movement of said conveyor in either direction of travel, a pair of cables, each of said cables having one of its ends anchored on a respective said drum and its other end anchored to said carriage, a pair of pulleys engaging respective of said cables, a pair of fluid cylinders having respective of said pulleys journaled on the outer ends of their piston rods, and pressurized fluid means operatively associated with the piston rod ends of said cylinders and with said control means for selectively applying a greater fluid pressure on the piston rod end of the piston of either cylinder than on the piston rod end of the piston of the other cylinder to thereby selectively pull one of said cables and release the other cable whereby the cable being pulled unwinds from its drum and responsively moves said conveyor and assembly while the cable being released winds on its drum responsive to turning of such drum by the conveyor.

6. The wheel washer of claim 1 in which said second double-acting means comprises a pair of sprockets journal-mounted on the ends of said carriage, an endless chain meshing with said sprockets and connected to said brush and nozzle assembly for shuttling said assembly responsive to turning of said sprockets, and turning means for selectively turning one of said sprockets in one direction

for advancing said assembly along said track by said chain and for turning the other sprocket in the opposite direction of rotation for returning said assembly along said track by said chain.

7. The wheel washer of claim 6 in which said turning means comprises a pair of drums coupled to said sprockets, a pair of cables each anchored to a respective said drum and to said carriage, a pair of pulleys engaging respective of said cables intermediate the drum and the carriage-anchored end of the cable, and fluid pressure means carried by said carriage for selectively pulling either of said pulleys and correspondingly releasing the other pulley whereby the cable on the pulley being pulled unwinds from its drum and responsively moves said chain and assembly while the cable on the pulley being released winds on its drum responsive to turning of its sprocket by said chain.

8. The wheel washer of claim 1 in which said control means includes a control arm carried by said brush and nozzle assembly in trailing relation thereto for vertical swinging movement in a plane parallel to said travel path, and includes a follower-roller journal mounted on the trailing end of said arm and projecting therefrom into said travel path behind the wheel being washed when said assembly is in wheel engaging position, said control means deactivating said second double-acting means responsive to engagement of said follower-roller with the back of said wheel whereby the advance of said assembly along said track is maintained at the same rate as the advance of said wheel along said travel path.

9. The wheel washer of claim 8 in which spring means is mounted on said carriage and is operatively connected with said control arm to yieldingly resist downward swing thereof, said follower-roller normally being located below the level of the axle of said wheel being washed whereby engagement of the follower-roller with the back of said wheel swings said arm downwardly in opposition to said spring means into a lowered position deactivating said second double-acting means.

10. The wheel washer of claim 1 in which said control means includes a self-opening valve which deactivates said second double-acting means when closed, and a control arm carried by said brush and nozzle assembly in trailing relation thereto for vertical swinging movement in a plane parallel to said travel path, a follower-roller journal mounted on the trailing end of said arm and projecting therefrom into said travel path behind the wheel being washed when said assembly is in wheel engaging position, spring means mounted on said carriage and operatively connected with said control arm to yieldingly resist downward swing thereof, said roller normally being located below the level of the axle of said wheel being washed whereby engagement of the roller with the back of said wheel swings said arm downwardly in opposition to said spring means into a lowered position, and cam means on said swing arm arranged to close said valve when said arm is in lowered position whereby the advance of said brush and nozzle assembly along said track is maintained at the same rate as the advance of said wheel along said travel path.

11. A wheel washer comprising, means for advancing a wheel to be washed along a given travel path, means for rotating said wheel considerably faster, rim speed considered, than the bodily speed of the wheel while being moved along said travel path, an elongated carriage paralleling said travel path and presenting a track therealong, a brush carried by said carriage, a nozzle assembly slidably mounted on said track, anchored first double-acting means for moving said carriage at cross-angles to said travel path, second double-acting means carried by said carriage for moving said assembly along said track, and control means responsive to the travel of a wheel along said travel path for selectively activating

ing said first and second double-acting means such as to cause said first double-acting means to move said carriage toward said travel path to bring said brush into wheel engaging position and to cause said second double-

5 acting means to advance said assembly along said track with the advancing wheel when said wheel is near the beginning of said track, and such as to cause said first double-acting means to move said carriage away from said travel path to remove said assembly from wheel 10 engaging position and to cause said second double-acting means to return said assembly to the beginning of said track when said wheel is near the end of said track.

12. A wheel washer comprising, means for feeding a wheel to be washed to and advancing the same through

15 the length of a given travel path, means for rotating the advancing wheel to give the same a rim speed appreciably faster than the travel speed, a carriage mounted to one side of said travel path for reciprocal motion in a direction transverse to the travel path inwardly toward and outwardly from the advancing wheel, a means tracking on the carriage for motion relative thereto in a direction longitudinal to the travel path, a wheel-washing instrument so supported by said tracking means as to be advanced into and retracted out of operating engagement 20 with the advancing wheel by the inwardly and outwardly directed transverse movement, respectively, of the carriage and to progress along said travel path in the same direction as the advancing wheel from a rear to a forward limit of prescribed travel by the movement of the tracking means in the forward stroke of its longitudinal reciprocation, returning to said rear limit of prescribed travel by the movement of the tracking means in the latter's rearward stroke of longitudinal reciprocation,

25 power means for moving the carriage and the tracking means in their respective reciprocal motions, and control means responsive to the travel of a wheel along said travel path for so activating said power means that the wheel-washing instrument is advanced into functioning engagement with the wheel as the wheel enters said travel path, 30 moves longitudinally in concert with the wheel as the wheel advances along said travel path, and is retracted from the wheel and returns longitudinally to said rear limit of longitudinal travel as the wheel leaves said travel path.

35 45 13. The wheel washer of claim 12 in which the power means for moving the carriage and the tracking means in their respective reciprocal motions are independent and comprise, in each instance, an axially movable piston working in a double-acting fluid cylinder.

40 50 55 14. The wheel washer of claim 13, the power cylinder for the tracking means being carried by the carriage with its axis normal to the path in which the carriage reciprocates, the rod of the related piston having two sprocket wheels mounted thereon for free rotation about an axis perpendicular to the slide axis of the piston, two chains being provided, each connected by one end to the tracking means, and extending in opposite directions therefrom parallel to said slide axis each to first take a half-turn about a respective sprocket wheel carried by the carriage, thence returning to take a half-turn around a respective one of the two piston-carried sprocket wheels, and having the other end dead-ended to the carriage.
